UNITED STATES PATENT OFFICE.

KARL F. GERHARD, OF HATTON, WASHINGTON.

CULTIVATOR.

1,265,902.

Specification of Letters Patent. Patented May 14, 1918.

Application filed August 28, 1916, Serial No. 117,339. Renewed March 19, 1918. Serial No. 223,466.

To all whom it may concern:

Be it known that I, KARL F. GERHARD, a citizen of the United States, residing at Hatton, in the county of Adams and State 5 of Washington, have invented certain new and useful Improvements in Cultivators, of which the following is a specification.

This invention relates to improvements in cultivators and weeders, and has particular reference to a wheeled cultivator for turning up the ground or cutting weeds over 10 a wide path.

An important object of the invention is to provide an easy means for raising the 15 cultivating points off the ground to avoid stumps or other obstructions, and to permit turning of the cultivator without injury to the points and their supports.

A further object of the invention is to 20 provide means for more easily and more accurately adjusting cultivating points than is provided for in existing cultivators.

A still further object of the invention is to make the lifting operation of the cultivating points subject to control from remote points; as for instance, from a traction engine which might be drawing the cultivator.

Other objects and advantages of the invention will be apparent during the course 30 of the following description.

In the accompanying drawings forming a part of this specification and in which like numerals are employed to designate like parts throughout the same,

Figure 1 is a plan view of my invention with some of the parts removed.

Fig. 2 is a vertical section on line 6—6 looking in the direction of the arrows. Some of the parts in this view are omitted.

Fig. 3 is a vertical section on line 7—7, also with certain parts omitted.

Fig. 4 is a perspective view of the operating gear for one-half of the cultivator.

Fig. 5 is a section view taken on line 8—8 of Fig. 3.

These drawings, for the purpose of illustration, show a preferred embodiment of my invention. The numeral 9 represents the main frame of the cultivator and is supported by the wheels 10 and tongue truck 11. The cultivator is drawn by tongue 12. Four racks 13 are attached to the frame by pivotal joints 14 carrying the blades 15. A brace 16 is mounted near the center of each rack, as shown. To these braces, rods 17 are pivotally mounted and adapted for ad-

justment by means of the holes 54. At the other end of the rod 17, threaded nuts 18 and washers 19 hold the helical springs 20. Loose sleeves 22 slip on the rods 17 and are held between the springs 20 and 21. The rear ends of springs 21 are held by cross pieces 23 and strap bolts 24 and hooks 55, as shown. The nuts 25 provide means for adjusting the tension of the springs. Pivotally mounted on the loose sleeves 22 are the forked cranks 26 carried by the shafts 27 for the forward racks and shafts 28 for the rear racks. These shafts are supported by bearing plates 29 and 30 and have solidly 60 attached thereto operating levers 31 and latch levers 32. Connecting rods 33 and 34 respectively, for the front and rear shafts 27 and 28, extend toward the main axle 35 and have rigidly fastened thereto upright 65 pieces 36. The main axle 35 is driven from the wheels 10 through ratchets in the hubs which are not shown, and so turns only when one or both wheels are moving forward.

Disks 37 fastened to axle 35 have mounted 80 thereon projecting pins 38. Rods 39 are attached to the connecting rods 33 and 34 and are raised or lowered by means of pedals 40 and 41. The raising of these rods 39 brings the projection 36 in the path of the 85 pins 38 as they revolve about shaft 35.

Latch levers 32 can be locked in their lower position by locking straps 42, as shown in Fig. 2. These locking straps 42 are pivoted on brackets 43 at 56. Near the upper 90 ends of the locking straps 42 are the slots 44 through which pass the cross pins 45 which pass through and are held at their centers by rods 46. Hand lever 47 passes up through the platform to which it is pivoted at 49 and terminates at its upper end in hand grip 59. At its lower end it is pivoted to rod 46 at 57.

The springs 50 carried on the lock straps 42, press the pins 45 against the rear of slots 44, but allow a slight movement so that the ends of latch levers 32 can swing down past notches 58 in locking straps 42 and thus lock without changing the position of rod 46.

The foot pedals 40 and 41 are held by 105 bearing plates 51 and can be operated individually, or they can be operated all simultaneously by depressing either of the master pedals 52.

The cultivator is drawn by horses hitched 110 to the tongue 10, or by a traction engine or by other suitable means. Ordinarily the

driver will occupy the seat 53 and in doing so can control the raising of the racks 13 either individually or collectively without greater effort than depressing the proper 5 foot pedal, and can lower all the racks by shifting the hand lever 47. For example, it is desired to raise one of the racks as in Fig. 3; the proper foot pedal is depressed and its connecting rod 34 brings the 10 projection 36 into contact with one of the pins 38. The pin is turning with the main axle 35 as the cultivator is advancing and thus forces the rod 34 rearward, causing shaft 28 to rotate, and in doing so to cause the 15 fork lever 26, which is rigidly fastened to the shaft, to move to the position as shown in Fig. 2. The sleeve 22 connected with 26 presses against the spring 20 and so causes the rod 17 to raise the rack 13 about the 20 joint 14, as shown in Fig. 2. In the raised position the shaft 27 (or 28) is locked by the latch lever 32 and the locking strap 42. In lowering the racks a slight movement of 25 the hand lever 47 swings locking strap 42 clear of the end of lever 32 and the weight of the rack then causes it to drop to a pre-determined, horizontal position, dependent upon the relative tensions of the springs 20 and 21, as shown in Fig. 3. The motion of 30 the rack in dropping is retarded by the compression of the spring 20 and its rebound motion is damped by spring 21.

It is to be understood that the form of 35 my invention herewith shown and described 40 is to be taken as a preferred example of the same, and that various changes in the shape, size and arrangement of parts may be resorted to without departing from the spirit of the invention or the scope of the subjoined claims.

Having thus described the invention, I claim:

1. In combination, a cultivator frame, an axle journaled in said frame, driving wheels 45 mounted on and adapted to revolve said axle, a cultivator rack pivotally connected to said frame, means for swinging said rack on its pivotal connection with said frame, said means comprising a brace secured to 50 and extending upwardly from said rack, a rod pivotally secured to said brace, a sleeve slidably mounted on said rod, springs encircling said rod and opposing the opposite sides of said sleeve, stops mounted on said 55 rod to position the outer ends of said springs, a shaft journaled to said cultivator frame, a crank non-rotatably mounted on said shaft and pivotally connected to said sleeve, means operated by said axle for rotating said shaft, 60 said last mentioned means comprising a disk mounted on said axle and adapted to be revolved by said axle, pins projecting from said disk, a lever mounted on said shaft, a connection rod pivoted at one end to said 65 lever, an upright piece secured to said con-

nnecting rod, means for moving said connecting rod to thrust said upright piece into the path of rotation of said projection pins, and means for retaining said shaft and said crank in a predetermined position at predetermined times, said means comprising a latch lever mounted on said shaft, and a locking strap for engaging said latch to retain said latch in a predetermined position. 70

2. In combination, a cultivator frame, an 75 axle journaled to said frame, driving wheels mounted on and adapted to revolve said axle, a cultivator rack pivotally connected to said frame, means for swinging said rack on its pivotal connection with said frame, 80 said means comprising a brace secured to and extending upwardly from said rack, a rod pivotally secured to said brace, a sleeve slidably mounted on said rod, springs encircling said rod and opposing the opposite 85 sides of said sleeve, stops mounted on said rod to position the outer ends of said springs, a shaft journaled to said cultivator frame, a crank non-rotatably mounted on said shaft and pivotally connected to said sleeve, means 90 operated by said axle for rotating said shaft, said last mentioned means comprising a disk mounted on said axle and adapted to be revolved by said axle, pins projecting from said disk, a lever mounted on said shaft, a 95 connection rod pivoted at one end to said lever, an upright piece secured to said connecting rod, means for moving said connecting rod to thrust said upright piece into the path of rotation of said projection pins, 100 means for retaining said shaft and said crank in a predetermined position at predetermined times, said means comprising a latch lever mounted on said shaft, and a locking strap for engaging said latch to retain said latch in a predetermined position; and means for manually disengaging said locking strap from said latch. 105

3. In combination, a cultivator frame, an axle journaled in said frame, means for revolving said axle, a cultivator rack pivotally connected to said frame, a shaft journaled in said cultivator frame, means for rotating said first mentioned shaft to swing said rack upwardly on its pivotal connection, said 110 means comprising a disk mounted on and adapted to be revolved by said axle, projecting pins on said disk, a lever mounted on said shaft, a connecting rod pivoted at one end to said lever, a member secured to 115 said rod, means for moving said connecting rod to thrust said member into a co-acting position with said pins, an operative connection between said rack and said shaft; means for retaining said rack in a raised position, 120 said means comprising a latch lever mounted on said shaft, and a locking strap for engaging said latch to retain said latch in a 125 predetermined position.

4. In combination, a cultivator frame, an 130

- axle journaled in said frame, means for revolving said axle, a cultivator rack pivotally connected to said frame, a shaft journaled in said frame, an operative connection between said rack and said shaft, a lever mounted on said shaft, a connecting rod pivoted at one end to said lever, means operated by said axle for shifting the position of said lever, means for retaining said rack 10 in a raised position, said means comprising a latch lever mounted on said shaft, and a locking strap for engaging said latch to retain said latch in a predetermined position.
5. In combination, a cultivator frame, an axle journaled in said frame, means for revolving said axle, a cultivator rack pivotally connected to said frame, a shaft journaled in said frame, an operative connection between said rack and said shaft, a lever mounted on said shaft, a connecting rod pivoted at one end to said lever, means operated by said axle for shifting the position 15 of said lever, a latch lever mounted on said shaft, a pivotally mounted locking strap, a spring for holding said strap in locking engagement with said lever, and means for swinging said strap on its pivotal mounting 20 for disengaging said strap from said latch lever.
6. In combination, a cultivator frame, an axle journaled in said frame, means for revolving said axle, a cultivator rack pivotally connected to said frame, a shaft journaled in said frame, an operative connection between said rack and said shaft, a lever mounted on said shaft, a connecting rod pivoted at one end to said lever, means operated by said axle for shifting the position 25 of said lever, a latch lever mounted on said shaft, a pivotally mounted locking strap, a spring for holding said strap in locking engagement with said lever.

In testimony whereof I affix my signature in the presence of two witnesses.

KARL F. GERHARD.
